UNITED STATES PATENT OFFICE.

JACOB SCHINNELLER, OF PITTSBURG, PENNSYLVANIA, ASSIGNOR OF ONE-HALF TO JAMES B. ARTHUR, OF WILKENSBURG, PENNSYLVANIA.

APPARATUS FOR ICING CAKES.

SPECIFICATION forming part of Letters Patent No. 623,185, dated April 18, 1899.

Application filed November 17, 1898. Serial No. 696,719. (No model.)

To all whom it may concern:

Be it known that I, JACOB SCHINNELLER, a resident of Pittsburgh, in the county of Allegheny and State of Pennsylvania, have invented a new and useful Improvement in Apparatus for Icing Cakes; and I do hereby declare the following to be a full, clear, and exact description thereof.

My invention relates to apparatus for applying icing to cakes.

The object of my invention is to provide a simple form of apparatus by means of which icing may be applied to cakes fed thereto in quick succession and with perfect uniformity of thickness, so that it is possible to handle large quantities in a short time without the employment of hand labor and at greatly-reduced cost.

To these ends my invention comprises the novel features hereinafter described and claimed.

To enable others skilled in the art to make and use my invention, I will describe the same more fully, referring to the accompanying drawings, in which—

Figure 1 is a side view of the apparatus. Fig. 2 is a plan view. Fig. 3 is a longitudinal section in elevation. Fig. 4 is a cross-section on line 4-4, Fig. 2. Fig. 5 is an enlarged longitudinal section showing more clearly the mechanism for supporting the cake during the icing operation and for discharging it when iced. Fig. 6 is an enlarged sectional view of a portion of the machine, being taken on same line as Fig. 4. Fig. 7 is a detail of mechanism for moving trays forward, and Fig. 8 is a detail in perspective showing means for releasing cake from plate.

Like letters of reference indicate like parts in each view.

The letter A designates a suitable frame or support for the apparatus mounted on the base-blocks A'. The main shaft a is mounted in suitable bearings a' in the frame A, said shaft being driven by the pulley a², connected up by belt to suitable source of power. A clutch a³, operated by the lever a⁴, is provided for throwing the shaft a into and out of connection with said pulley.

At each end of the shaft a are the eccentrics b, whose rods b' extend back and con-

nect with the sliding pusher-frame C at b². This frame C is composed of the cross-bar c, with the bearings c' at each end thereof engaging with the rods c², on which said frame 55 slides back and forth. The bar c is made in the form of a channel-bar, with the slot c³ formed therein. The pushers c⁴ are secured to the bar c by means of the bolts c⁵, whose heads engage the bar on its interior, while the 60 nuts c⁶ secure the pushers in position. The pushers have slots c⁷, by means of which said pushers may be adjusted longitudinally, according to the size of cakes they are to operate on. These pushers are arranged at intervals, and their number may be increased or diminished, according to the capacity of the apparatus.

Below the pushers c⁴ are the pans d, which are made to conform to the size and shape of 70 the cakes to be iced. It is into these pans that the cakes d' drop from the feed-boxes d² when the pushers have been withdrawn. These feed-boxes are supported above the pans and the cakes are fed to them by means 75 of the chutes d³. Within the chute d³ is the stop d⁴, which acts to arrest a cake which has been fed to the chute bottom up or which has become inverted in its course down the chute. As the cakes illustrated have rounded bottoms, if they become inverted they will not fit the rounded bottom of the chute, but will extend up above the stop d⁴. The boxes correspond in size and shape to the size and shape of the cakes, and as the cakes are fed 85 thereto they arrange themselves one on top of the other in the manner illustrated.

Above the pushers c⁴ is the plate or table e, supported by the frame in any suitable manner. This plate e has the openings e' formed 90 therein, corresponding substantially in size and shape to the cakes and in line with the pushers c⁴. Other plates with openings of different size and shape may of course be substituted for the plate illustrated.

A hopper f is arranged transversely of the plate e and is adapted to move across said plate. A reciprocating movement is imparted to the hopper f by means of the eccentrics g on the shaft a. Rods g' connect said eccentrics with the hopper f at each end thereof.

Below the plate *e* in line with each opening *e'* are the cake-supporting blocks *h*, upon which are supported the cushions *h'* of sponge-rubber, or other suitable material. These blocks *h* are carried by the rocking frame *i*, supported by the arms *k* in the manner more fully hereinafter set forth. Bolts *j* enter the blocks *h* from below and flanges *j'* on said bolts bear against the lower faces of said blocks. The bolts pass through openings in the upper and lower bars *i'* *i''* of the frame *i*, while a threaded collar *j''* engages the upper threaded opening *i'''* in the upper bar *i'* of the frame. This collar *j''* has the head *j''* for the purpose of turning said collar. In this manner the height of the blocks may be regulated. On the lower ends of the bolts *j* are the jam-nuts *j''*.

The rocking frame *i*, as above set forth, is pivoted at its ends to the arms *k*. These arms *k* are pivoted at their forward ends, as at *k'*, to the frame *A*, the rear ends of said arms fitting in the guides *k''*. The set-screw *k'''* regulates the downward movement of the rear ends of said arms. In the rocking frame *i* are the set-screws *k''*, which are adapted to come in contact with the arms *k* as said frame is raised and move said arms until they are stopped by the guides *k''*, as will more fully 30 hereinafter appear.

Secured to the shaft *l*, journaled in the frame *A*, is the lever *m*, the forward end of said lever having the projection *m'*, adapted to engage the cam *n* on the shaft *a*. Arms *o*, secured to the shaft *l*, have their rear ends engaging the openings *i''* in the trunnions *i'*, mounted in the uprights *i''* of the rocking frame *i*.

Chutes *p* are arranged in such position with reference to the blocks *h* as to receive the cakes discharged therefrom when said blocks are tilted in the manner more fully herein-after set forth.

A releasing device is employed to prevent the cakes from adhering to the plate *e* after the icing operation. This device consists of the arm *r*, secured to the shaft *s*. The forward end of the arm *r* has the stud *r'*, adapted to be engaged by the knocker *r''* on the collar *r'''* on the shaft *a*. Secured to the shaft *s* are the arms *s'*, which extend rearwardly therefrom. These arms *s'* pass underneath the plate *e*, and at their rear ends are the inwardly-projecting lips *s''*, which are adapted to engage the edges of the cakes, as shown in Fig. 8, so that upon each revolution of the shaft *a* the knocker *r''* will raise the arm *r* and lower the arms *s'* with their lips *s''*. This movement of said lips will act to release the cakes in case they adhere to the plate *e* after the blocks have been partially withdrawn.

Underneath the frame *A* is the conveying device for receiving and carrying away the cakes coming from the chutes *p*. The trays *t* for receiving the iced cakes move in the guide-way *t'*. An endless chain *u* on the sprocket-wheels *u'* has projections *u''* extending out

therefrom, adapted to engage the trays and carry them forward by an intermittent movement. On the sprocket-wheel shaft *v* is the ratchet *v'*. A crank-arm *w* on the shaft *v* has the pawl *w'* pivoted thereto, with the spring *w''* pressing against same. On the outer end of main driving-shaft *a* is keyed the disk *y*, to which is pivoted the link *y'*. The lower end of link *y'* is connected to the outer end of arm *w*, as at *y''*. As the disk *y* revolves with the main shaft *a* the arm *w* is raised and lowered through the link *y'*. As the arm *w* is raised the pawl *w'*, coming in contact with one of the teeth of ratchet-wheel *v'*, acts to partially revolve the shaft and sprocket-wheel *u'* thereon. At each revolution of the shaft *a* the sprocket-wheel *u'* is partially revolved and the trays *t* are moved along step by step a sufficient distance to receive the cakes coming from the chutes. At the foot of the chutes *p* is the guard *p'*, made of rubber or other yielding material, said guard being supported from the frame *p''*. In case the cakes as they are discharged from the chutes *p* travel with sufficient force to go beyond their proper position on the trays the guard *p'* will check their progress and keep them all substantially in line on the trays. Owing to the yielding character of the guard it will not break or injure the cakes.

When the tray has been filled with cakes, it is necessary to move it forward a sufficient distance so that the succeeding tray may be moved a corresponding distance to clear the end pieces of both trays and deposit the cakes properly in the box. For this purpose the arm *w* has a greater throw than is necessary to drop from tooth to tooth of the ratchet. One of the teeth *v''* covers a greater space on the circumference of the ratchet than the others, so that when it is caught by the pawl it will revolve the shaft *v*, and consequently sprocket *u'*, a greater distance than at other times, so that the trays *t* are moved a sufficient distance to allow for the cakes plus the width of the two end pieces of the trays.

The operation of the apparatus is as follows: The cakes are fed to the boxes *d''* and the icing or other material of the proper consistency is introduced into the hopper *f*. The operator then throws the lever *a''* over to bring the shaft *a* into engagement with the revolving pulley. As the shaft *a* rotates the eccentric *b* act to draw forward the rods *b'* and with them the pusher-frame *C*. The individual pushers *c'* each act to advance a cake from its corresponding pan *d* in line therewith. These cakes are pushed forward until they are brought directly under the openings *e'* in the plate *e*, when the forward movement of said pushers ceases. Meanwhile the blocks *h* have been raised into position substantially level with bottoms of pans *d* to receive the cakes, and it is upon the cushions of these blocks that the cakes now rest. By the mechanism hereinafter referred to the blocks are further elevated to the plate *e*. By this time

- the eccentrics g are in position to move back the hopper f over the plate e . The hopper travels back and over the openings e' , under which the cakes rest. The icing is deposited on the cakes and then the eccentrics g draw forward the hopper, leaving a layer of icing on the cakes corresponding to the thickness of the plate e . The movement of the hopper in close contact with the plate e and across the openings e' leaves an even and uniform deposit of the icing on each cake. The cushioned blocks prevent the breaking of the cakes, as if there is undue pressure brought to bear on the cakes said blocks will yield.
- 15 During this operation the cam n has been moving with its regular periphery n' moving in contact with the projection m' on the lever m , whereby the blocks h are held up in position during the icing operation; but after the 20 hopper has passed back and forth the cam portion n^2 of the cam n now moves into contact with the projection m' of the lever m . This permits said lever to assume the position shown in dotted lines, Fig. 5, whereupon the 25 arms o are lowered, and with them the rocking frame i is first slightly lowered in vertical plane and then tilted together with the blocks h . During this first slight downward movement of the blocks, if the cakes should 30 adhere to the lower face of the plate, the lips s^2 on the arms s' will act to release the cakes from said plate, so that they are carried down by said blocks. By then tilting the blocks in the manner shown they are brought 35 into such position with reference to the chutes, p as to discharge the cakes into said chutes, whence they pass down the trays t in regular order, to be carried away in the manner above set forth. After the cakes have 40 been discharged from the blocks h the cam has revolved sufficiently to bring the cam portion n^3 into contact with the end of the lever m , when said blocks, together with the rocking frame i , begin to move back to their 45 original position to receive the next lot of cakes to be iced. This movement of the rocking frame continues until the blocks have been brought back to substantially a horizontal position, and while the blocks are being 50 brought back the pushers c^4 push the cakes onto the blocks, so that when the blocks have arrived at a horizontal position the cakes will be resting thereon. A further revolution of the cam n brings the cam portion n^4 into contact with the lever m . Having by the previous movement of the cam n brought the blocks to a horizontal position it is desirable to elevate the blocks evenly in a vertical plane, so that the cakes will have all points 55 of their upper surface presented for icing at the same time. To accomplish this, the rocking frame i is hinged to the arms k , which are free to move up and down in the guides k^2 , the amount of their movement being regulated by the set-screw k^3 . After the rocking frame i has been brought to its horizontal 60 position the set-screws k^4 are in contact with the arms k , so that any further movement imparted to said frame by the lever l must be in a vertical plane, as the set-screws 70 raise the arms k in their guide k^2 . When, therefore, the cakes have been deposited onto the blocks h , the cam portion n^5 of cam n moves into contact with the arm m , whereupon the blocks are elevated in a vertical 75 plane until they bring the cakes up against the lower face of the plate e in line with the openings e' . The hopper f again travels back and forth to apply a layer of icing to the cakes as before. In the above manner 80 the cakes are iced in rapid succession, the only requirement in the way of manual labor being an attendant to feed the cakes to the apparatus. The icing is applied with even thickness to all the cakes, and an even smooth 85 surface is imparted to each cake.
- I do not wish to confine myself to the exact construction illustrated, as that may be modified without affecting the scope of my invention. Furthermore, I wish to include 90 all uses to which the apparatus may be found applicable, and do not wish to restrict it simply to the icing of cakes.
- What I claim as my invention, and desire to secure by Letters Patent, is— 95
1. The combination with a suitable frame, of a table having an opening therein, a hopper above said table, mechanism for moving said hopper back and forth over said opening, a support beneath said opening, mechanism for raising and lowering said support, and charging mechanism in line with said support, substantially as set forth. 100
  2. The combination with a suitable frame, of a table having an opening therein, a hopper above said table, mechanism for moving said hopper back and forth over said opening, a support beneath said opening, and mechanism for tilting said support, substantially as set forth. 105
  3. The combination with a suitable frame, of a table having an opening therein, a hopper above said table, mechanism for moving said hopper back and forth over said opening, a support beneath said opening, mechanism for tilting said support, and mechanism for elevating said support vertically, substantially as set forth. 110
  4. The combination with a suitable frame, of a table having an opening therein, a hopper above said table, mechanism for moving said hopper back and forth over said opening, a tilting frame beneath said table, a support on said tilting frame, a shaft, a cam on said shaft, and connections between said cam and said tilting frame, substantially as set forth. 120
  5. The combination with a suitable frame, of a table having an opening therein, a hopper above said table, mechanism for moving said hopper back and forth over said opening, a tilting frame beneath said table, a support on said tilting frame, a shaft, a cam on said 125

shaft, a lever in the path of said cam and actuated thereby, and connections between said lever and said tilting frame, substantially as set forth.

5 6. The combination with a suitable frame, of a table having an opening therein, a hopper above said table, mechanism for moving said hopper back and forth over said opening, a tilting frame beneath said table, a support on said tilting frame, a shaft, a cam on said shaft, a lever in the path of said cam and actuated thereby, a rock-shaft on which said lever is mounted, and an arm on said shaft engaging said tilting frame, substantially as set 15 forth.

15 7. The combination with a suitable frame, of a table having an opening therein, a hopper above said table, mechanism for moving said hopper back and forth over said opening, a tilting frame beneath said table, a support on said tilting frame, a shaft, a cam on said shaft, a lever in the path of said cam and actuated thereby, a rock-shaft on which said lever is mounted, an arm on said shaft, and a 25 trunnion on said tilting frame with which said arm engages, substantially as set forth.

30 8. The combination with a suitable frame, of a table having an opening therein, a hopper above said table, mechanism for moving said hopper back and forth over said opening, a swinging arm, a tilting frame on said arm, a support on said tilting frame, and mechanism for tilting said frame and raising it up into position, substantially as set forth.

35 9. The combination with a suitable frame, of a table having an opening therein, a hopper above said table, mechanism for moving said hopper back and forth over said opening, a swinging arm, a tilting frame on said arm, a support on said tilting frame, said tilting frame moving in the path of said swinging arm and adapted to raise same, and mechanism for tilting said tilting frame and raising it up in position, substantially as set forth.

45 10. The combination with a suitable frame, of a table having an opening therein, a hopper above said table, mechanism for moving said hopper back and forth over said opening, a swinging arm, a stop for said arm, a tilting frame on said arm, a support on said tilting frame, a set-screw on said tilting frame adapted to engage said arm and raise same and mechanism for tilting said frame and raising it up in position, substantially as set forth.

55 11. The combination with a suitable frame, of a table having an opening therein, a hopper above said table, mechanism for moving said hopper back and forth over said opening, a support beneath said opening, mechanism for raising and lowering said support, and a releasing device adapted to release the article.

60 12. The combination with a suitable frame, of a table having an opening therein, a hopper above said table, mechanism for moving said hopper back and forth over said opening, a support beneath said opening, mechanism for

raising and lowering said support, releasing-arms adapted to engage the article on said support, and mechanism for raising and lowering said arms, substantially as set forth. 70

13. The combination with a suitable frame, of a table having an opening therein, a hopper above said table, mechanism for moving said hopper back and forth over said opening, a support beneath said opening, mechanism for 75 raising and lowering said support, a shaft, releasing-arms on said shaft, a rocker-arm on said shaft, and mechanism for rocking said arm, substantially as set forth.

14. The combination with a suitable frame, 80 of a table having an opening therein, a hopper above said table, mechanism for moving said hopper back and forth over said opening, a support beneath said opening, mechanism for raising and lowering said support, a shaft, releasing-arms on said shaft, a rocker-arm on 85 said shaft, a main shaft, and a knocker on said main shaft adapted to engage said rocker-arm, substantially as set forth.

15. The combination with a suitable frame, 90 of a table having an opening therein, a hopper above said table, mechanism for moving said hopper back and forth over said opening, a support beneath said opening, mechanism for raising and lowering said support, a shaft, releasing-arms on said shaft, inwardly-extending lips on said arms, a rocker-arm on said shaft, a main shaft, and a knocker on said main shaft adapted to engage said rocker-arm, substantially as set forth. 95

16. The combination with a suitable frame, of a table having an opening therein, a hopper above said table, mechanism for moving said hopper back and forth over said opening, a support beneath said opening, mechanism for 105 raising and lowering said support, a pusher in line with said support, and mechanism for advancing and withdrawing said pusher, substantially as set forth.

17. The combination with a suitable frame, 110 of a table having an opening therein, a hopper above said table, a main shaft, connections between said shaft and said hopper for reciprocating same, a support beneath said opening, mechanism for raising and lowering 115 same, a chute in line with said support, a carrier at the lower end of said chute and mechanism for imparting an intermittent movement to said carrier, substantially as set forth.

18. The combination with a suitable frame, 120 of a table having an opening therein, a hopper above said table, a main shaft, connections between said shaft and said hopper for reciprocating same, a support beneath said opening, mechanism for raising and lowering 125 same, a chute in line with said support, a carrier at the lower end of said chute and connections between said main shaft and said carrier, whereby said carrier is advanced a certain distance at one revolution of said shaft 130 and an increased distance at another, substantially as set forth.

19. The combination with a suitable frame, of a table having an opening therein, a hopper above said table, a main shaft, connections between said shaft and said hopper for reciprocating same, a support beneath said opening, mechanism for raising and lowering same, a chute in line with said support, a carrier at the lower end of said chute, a sprocket-wheel, an endless chain engaging said carrier, a ratchet on said sprocket-wheel, said ratchet having an increased distance between two of its teeth, an arm on the sprocket-wheel shaft, a pawl on said arm engaging said ratchet, and connections between said arm and said main shaft, whereby an oscillating movement is imparted to said arm, substantially as set forth.

20. The combination with a suitable frame, of a table having an opening therein, a hopper above said table, a main shaft, connections between said shaft and said hopper for reciprocating same, a support beneath said opening, mechanism for raising and lowering same, a chute in line with said support, a carrier at the lower end of said chute, and a

yielding guard at the lower end of said chute, substantially as set forth.

21. The combination with a suitable frame, of a table having an opening therein, a hopper above said table, the latter being movable back and forth with reference to the former, a support beneath said opening, mechanism for raising and lowering said support, a feed-box, and mechanism for transferring the article to be coated from said feed-box to said support, substantially as set forth.

22. The combination with a suitable frame, of a table having an opening therein, a hopper above said table, mechanism for moving said hopper back and forth over said opening, a support beneath said opening, a cushion on said support, and mechanism for raising and lowering said support, substantially as set forth.

In testimony whereof I, the said JACOB SCHINNELLER, have hereunto set my hand.

JACOB SCHINNELLER.
